UNITED STATES PATENT OFFICE

96,428

DESIGN FOR A CASING FOR AUTOGRAPHIC
REGISTERS

Walter D. Teague, New York, N. Y., assignor, by
mesne assignments, to American Sales Book
Company, Inc., a corporation of Delaware

Application December 7, 1934, Serial No. 54,331

Term of patent 14 years

To all whom it may concern:

Be it known that I, Walter D. Teague, a citizen of the United States, residing at New York, in the county of New York and State of New York, have invented a new, original, and ornamental Design for a Casing for Autographic Registers, of which the following is a specification, reference being had to the accompanying drawing, forming part thereof.

Fig. 1 is a perspective view of a casing for an autographic register showing my new design;

Fig. 2 is a top plan view of the same;

Fig. 3 illustrates the ornamental design in side elevation;

Fig. 4 is an end elevation of one end of the casing;

Fig. 5 is an end elevation of the opposite end of the casing; and

Fig. 6 is a transverse section on the line 6—6 of Fig. 5, showing the fluted contour of this part of the casing. A similar fluted contour appears at the opposite end of the casing, as illustrated in Fig. 4.

I claim:

The ornamental design for a casing for autographic registers, as shown and described.

Signed at New York, in the county of New York and State of New York, this 26th day of November, 1934.

WALTER D. TEAGUE.
